UNITED STATES PATENT OFFICE

NOEL S. DUNBAR, OF NEW YORK, N. Y., ASSIGNOR TO THOMAS A. EDISON, INCORPORATED, OF WEST ORANGE, NEW JERSEY, A CORPORATION OF NEW JERSEY

DESIGN FOR A COMBINED RADIO AND PHONOGRAPH CABINET OR SIMILAR ARTICLE

Application filed December 29, 1928. Serial No. 29,455. Term of patent 7 years.

To all whom it may concern:

Be it known that I, NOEL S. DUNBAR, a citizen of the United States, residing at New York, in the county of New York and State of New York, have invented a new, original, and ornamental Design for Combined Radio and Phonograph Cabinets or Similar Articles, of which the following is a specification, reference being had to the accompanying drawings, forming part thereof.

In the drawings:

Figure 1 is a perspective view of a combined

radio and phonograph cabinet or similar article embodying my new design, showing the front doors in closed position;

Fig. 2 is a perspective view of the combined radio and phonograph cabinet or similar article illustrated in Fig. 1, with the front doors thereof shown in open position.

I claim:

The ornamental design for a combined radio and phonograph cabinet or similar article, as shown.

NOEL S. DUNBAR.
